(57) **CLAIM**

The ornamental design for a tool handle, as shown and described.

DESCRIPTION

FIG. 1 is a front perspective view of the tool handle of the present invention showing my new design;

FIG. 2 is a front elevational view thereof;

FIG. 3 is a back elevational view thereof;

FIG. 4 is side elevational view thereof;

FIG. 5 is another side elevational view thereof;

FIG. 6 is a bottom plan view thereof; and,

FIG. 7 is a top plan view thereof.

The broken lines on the body of the tool handle illustrate details that form no part of the claim. The broken lines below the tool handle illustrate environment and also form no part of the claim.

1 Claim, 6 Drawing Sheets
